UNITED STATES PATENT OFFICE

2,228,979

LATCH ASSEMBLY

Thomas O. Schrader, Fullerton, Pa., assignor to
 Dent Hardware Company, Fullerton, Pa., a corporation of Pennsylvania

Application October 28, 1938, Serial No. 237,555

16 Claims. (Cl. 292—173)

This invention relates to closure fasteners and is more particularly concerned with latch assemblies and operating mechanisms for closure members.

5 The latches of the present invention have been designed especially for use on bulky closure members, such as refrigerator doors, although it will be understood that the invention is equally applicable to any type of closure member.

10 Large commercial refrigerators, such as those used in grocery stores, are usually provided with a plurality of doors at upper and lower levels. These doors are ordinarily provided with pivoted latch operating handles which are grasped and pulled outwardly by the operator when it is desired to open the doors.

In order to render these handles readily accessible to the operator, the handles of the top doors usually extend downwardly from their 20 pivots on the doors while the handles on the lower doors are usually arranged to extend upwardly from their pivots on the door.

Furthermore, in order to render groups of handles readily accessible to an operator from one 25 standing position, adjacent doors are hinged to swing in opposite directions so that their latches are adjacent when the doors are closed.

Heretofore, it has been a common practice to manufacture separate latch mechanisms for doors 30 which swing in opposite directions and for doors at different levels wherein the position of the latch handles are reversed. This has been necessary, of course, because for example the ordinary latch designed for a door swinging to the left 35 could not be used upon a door which swings to the right.

As a result of this situation, latch manufacturers are compelled to make latch constructions in several classifications according to their use 40 and refrigerator builders have been compelled to carry a complete stock of all these different latch classifications.

With the above situation in mind it is a major 45 object of my invention to provide a novel reversible latch assembly for swingable closure members or the like which is universally applicable to these closure members regardless of how the latter are swingably mounted and regardless of the position of the handles. More specifically, 50 my improved latch assembly can be mounted upon any door or the like whether it swings to the right or left, or up or down, or whether it is desired to arrange the handles to extend upwardly or downwardly from their pivots, or in any other 55 directions.

A further object of my invention is to provide a novel association of a latch mechanism and a handle mechanism for operating the same wherein the two are so mounted upon the closure member that either may be removed for repair or replacement without removing the other. Specifically the latch bolt operating mechanism is substantially entirely enclosed in a housing which is insertable into the door as a unit while the handle mechanism is also a separate unit secured 10 to the door and provided with a projecting cam arm for contacting and operating the latch mechanism.

A further object of my invention is to provide a novel association of a latch mechanism and a handle mechanism for operating the same which 15 may be cooperatively associated upon a swingable closure member regardless of the direction of swinging of said closure member and regardless of the direction in which it is desired that the 20 handle will extend.

A further object of the invention is to provide a novel latch mechanism which can be mounted adjacent an edge wall of a swingable closure regardless of the direction of swinging of said closure member. Specifically my novel latch mechanism is provided with a pair of independently 25 operable latch bolt operating arms, at least one of which is available for actuation by the handle mechanism whatever the position of the latch 30 mechanism.

A further object of the invention is to provide a novel latch bolt operating mechanism wherein a simplified lever arrangement is actuated to move the latch bolt. Specifically a pair of these 35 lever arrangements providing alternative control for the latch bolt are included in the latch mechanism so that the latter may be universally and reversibly mountable on any closure member.

It is a further object of the invention to provide 40 a novel latch operating handle mechanism having cam means engaging the latch mechanism wherein relatively small movement of the handle effects complete travel of the latch bolt. Specifically this cam means may comprise an elongated 45 curved lever rigid with the handle and arranged with its free end substantially contacting an operating arm of the latch mechanism within the closure member.

A further object of the invention is to provide 50 a novel adjustable keeper mechanism for cooperation with doors of different thicknesses and gasket size.

Further objects of the invention will presently appear as the description proceeds in connection 55

with the appended claims and the annexed drawings in which:

Figure 1 is a side elevation of a latch assembly of the invention with the cover of the latch mechanism removed and the parts arranged with the latch handle upon the front wall of the door and hanging downward vertically as it would at the upper doors of a commercial refrigerator, and with the door arranged to swing about a vertical axis to the left of Figure 1.

Figure 2 is an end view of the latch mechanism of Figure 1, looking from left to right therein, illustrating the dual latch bolt operating arms and the relation of the handle operated cam lever thereto.

Figure 3 is a side elevation, partly in section, of the novel handle mechanism.

Figure 4 is a section taken generally along line 4-4 in Figure 1 illustrating the latch bolt arrangement with the cover on the latch mechanism and illustrating further association of a latch operating arm with the handle operated cam lever.

Figure 5 is a side elevation of the cover for the latch mechanism.

Figure 6 is an end view of the cover of Figure 5.

Figure 7 is an end elevation of an adjustable keeper mechanism of the invention.

Figure 8 is a side elevation of the latch assembly of Figure 1 arranged upon a door mounted to swing about a vertical axis to the right of Figure 8 and with the pivoted handle at the front wall of the door extending downwardly.

Figure 9 is a side elevation of the latch assembly of Figure 1 arranged upon a door mounted to swing about a vertical axis to the right of Figure 9 and with the pivoted handle at the front wall of the door extending upwardly as it would at the lower doors of a commercial refrigerator.

Figure 10 is a side elevation of a modified form of latch mechanism, with the cover off, adapted for use on doors where the frame width is relatively small.

Figure 11 is a section taken along line 11-11 of Figure 10 illustrating the latch bolt arrangements.

Referring to Figure 1, a closure member or door 12 is provided at a vertical frame wall member 13 with a suitable recess for receiving a housing 14 containing a latch mechanism. Housing 14 is fitted into the frame member in such a manner that its outer end wall 15 fits substantially flush with the adjacent surface of member 13.

Housing 14 comprises end wall 15, a side wall 16, parallel top and bottom walls 17 and 18 respectively, an inner end wall 19 parallel to wall 15 and a pair of inclined walls 21 and 22 extending from opposite ends of wall 19 to adjacent ends of walls 17 and 18, respectively. Walls 15-19, 21 and 22 are rigid with each other to form the generally cup shaped housing 14 and preferably housing 14 is a single casting.

The open side of housing 14 is enclosed by a suitably shaped cover 23, illustrated in Figures 5 and 6. A threaded post 24 upstanding from wall 16 is adapted to receive the end of a screw 25 which passes through a suitable aperture 26 in cover 23 to fasten the cover to the housing.

With cover 23 in place, housing 14 is secured to frame member 13 by screws 27 which extend through suitable apertures in oppositely projecting extensions of wall 15.

The inner portion of housing 14 projects beyond frame member 13 into a hollow portion of the door where it is cooperatively associated with

a handle mechanism actuated from the front wall of the door as will be described.

Inside housing 14, a latch bolt 28, having an enlarged head portion 29 extending through an aperture 31 in wall 15, is slidably mounted. The rear portion of bolt 28 extends through a suitable aperture in supporting wall 19 and a coiled compression spring 32 which surrounds bolt 28 and extends between wall 19 and the inner surface of head 29 urges the latch bolt toward the right in Figure 1.

One side edge of head 29 is provided with a projection 33 which fits within an aligning guide recess 34 formed in wall 16. The opposite side of head 29 fits within a similar guide recess 35 formed in cover 23. Guide recesses 34 and 35 and the bolt receiving apertures in walls 15 and 19 cooperate to insure movement of the latch bolt in a path generally normal to the edge of the door. Cover 23 is provided at its front edge with a projection 30 which fits within the walls of aperture 31 when the cover is in place upon the housing so as to promote speedy assembly of the latch mechanism.

That portion of head 29 which extends outside housing 14 has an inclined surface and is of conventional shape for cooperating with a suitable keeper and need not be further described.

Within housing 14, head 29 is provided with a pair of oppositely extending projections 36 and 37. A pair of double armed levers or pawls 38 and 39 are loosely mounted upon suitable pivot posts 41 and 42 respectively upstanding from wall 16 at opposite sides of the latch bolt. Posts 41 and 42 as well as post 24 are preferably cast integral with housing 14.

Lever 38 is formed with a downwardly extending curved arm 43 which fits into the space between projection 36 and the inner surface of wall 15. Lever 39 is provided with a similar upwardly extending curved arm 44 which fits into the space between projection 37 and the inner surface of wall 15. The force exerted by spring 32 upon head 29 tends to maintain projections 36 and 37 in firm contact with lever arms 43 and 44, respectively.

Arms 43 and 44 may cooperate with wall 15 to serve as stops limiting outward movement of bolt 28, and wall 15 may serve as an abutment for restricting rotation of levers 38 and 39 in a counterclockwise and clockwise directions respectively about their pivot axes.

Levers 38 and 39 extend rearwardly through suitably enlarged apertures 45 and 46 in walls 21 and 22 respectively and terminate well beyond wall 19 as shown in Figure 1. When door 12 is closed, as illustrated in Figure 1, levers 38 and 39 extend practically parallel to each other and to the bolt 28. Apertures 45 and 46 are of sufficient size to enable pivotal movement of levers 38 and 39 during actuation of the latch bolt and the adjacent edges of these apertures may cooperate with wall 15 to serve as stops restricting rotation of the levers.

Referring to Figures 1, 2 and 3, an escutcheon plate 47 of any suitable shape or design is secured to a front frame member 50 of door 12 by screws 48 or similar fastening means. Plate 47 is provided with an apertured portion adjacent one end through which extends a generally horizontal pivot pin 49 upon which is mounted a handle member 51 having a downwardly projecting grip portion 52 exteriorly of the door and extending generally parallel to the front surface thereof.

An elongated, downwardly curved cam lever 53,

rigid with member 51, extends through a suitable aperture in frame member 47 into the hollow interior of the door. Preferably members 51, 52 and 53 are formed as an integral piece.

- 5 Handle member 51 is urged in a counterclockwise direction in Figure 3 by the action of a suitable spring 54 which is coiled about pin 49 at opposite sides of member 51 and whose opposite ends bear against the under side of lever 53 and a
 10 rigid rib 55 integral with plate 47. Suitable shoulders 56, formed on opposite sides of member 51, form spring pockets about the pivot pin. Any suitable resilient means can be used in place of spring 54 for the same purpose.
 15 With the handle grip 52 in the released position and the door closed as shown in Figure 1, the lower inner end of cam lever 53 rests in substantial contact with the top surface of the latch bolt operating arm 39. It is not necessary that
 20 lever 53 actually be in contact with arm 39 although this arrangement is preferable for speedy and satisfactory operation. In this position the door is held closed by engagement of latch bolt head 29 with a suitable keeper on the doorway
 25 frame.

In order to open the door, grip 52 is pulled outwardly away from the door thereby rotating handle member 51 in a clockwise direction about its pivot 49, and the displaced lower end of cam lever 30 53 which engages the upper surface of lever 39 causes lever 39 to be rotated in a counterclockwise direction in Figure 1. As lever 39 rotates in this direction, arm 44 cooperates with projection 37 to slide latch bolt 28 to the left against the 35 action of spring 32, thereby withdrawing head 29 from the keeper.

When head 29 clears the keeper, continued outward pull on the handle grip 52 will result in opening of the door.

40 It will be observed that the upper lever 38 is absolutely inoperable upon the latch bolt in this arrangement and the above described action takes place just as though lever 38 were not present. Therefore, it is obvious that the simplified lever 45 structure of the invention can be applied to irreversible as well as reversible latches.

When handle grip 52 is released, spring 54 forces the cam lever 53 upwardly with respect to the lever 39 and permits spring 32 to restore the 50 latch mechanism to the position shown in Figure 1.

When the door is being closed spring 32 permits retraction of the latch bolt until head 29 has cleared the keeper and then forces the bolt 55 to the right into the keeper pocket in the position shown in Figure 1. No manipulation of the grip handle is necessary to effect closure of the door.

An adjustable keeper which has been found to 60 be of great value for use with doors of different thicknesses or doors which have different gasket thicknesses along their edges is illustrated in Figure 7. A base plate 56 is formed with a central recess 57 flanked at the top and bottom by two rows of serrations 58.

The top plate 59 is formed with a central aperture 61 which is also flanked at the top and bottom by two rows of serrations 62 which are adapted to interfit with serrations 58 on the base 70 plate with aperture 61 disposed above recess 57. Plate 59 is also formed at its front edge with a latch bolt head engaging projection 63.

Plate 59 is provided with a pair of elongated slots 64 aligned with suitable apertures 65 in the bottom plate so that plate 59 may be secured in

any laterally adjusted position along plate 56 as desired and both plates secured to the doorway by screws passing through slots 64 and apertures 65 into the doorway frame.

In Figure 8 the latch assembly of Figure 1 is 5 illustrated as mounted upon a door which swings in the opposite direction from that of Figure 1. In such an arrangement the latch is reversed and lever 39 cannot be operated by the handle hanging downwardly from its pivot. However, 10 the latch mechanism is now operable by the engagement of cam lever 53 with the duplicate latch operating lever 38 and manipulation of handle grip 52 will produce the same operation as above described in Figure 1 except that here the motion is transmitted to the latch bolt through lever 38, arm 43 and projection 36.

In Figure 9 the latch assembly of Figure 1 is 20 applied to a low door which swings in the same direction as that of Figure 8. In this arrangement the handle grip 52 is reversed and extends upwardly, and the cam lever 53 engages the operating arm 39.

Modification

The latch mechanism illustrated in Figures 10 25 and 11 is designed for use on doors where the frame walls are narrow and where there is not sufficient room to insert the construction illustrated in Figure 1.

In general this mechanism is mounted upon a 30 housing 66 quite similar to housing 14 in shape but compressed laterally as shown in Figure 10. Housing 66 is provided with a suitable cover 70 as illustrated in Figure 11.

Latch bolt 67 comprises a block having a channel 68 therein which houses a spring 69 whose rear end abuts against the rear wall 71 of the housing. Bolt 67 is formed with a pair of integral ears 72 and 73 which are urged by spring 69 into contact with a pair of double armed levers 74 and 75, respectively in the same manner as the construction above described in Figure 1.

Levers 74 and 75 are appreciably shorter than levers 38 and 39 of Figure 1 and preferably terminate in substantial vertical alignment with 45 wall 71. Sufficient space is provided, however, between the inclined walls 76 and 77 of the housing and those levers to permit insertion of the lower end of cam lever 53 of the handle assembly 50 so that the latch mechanism of Figures 10 and 11 is operable by the handle mechanism of Figure 3 in exactly the same manner as above described.

The latch mechanism of Figures 10 and 11 is 55 also reversible in the same manner as that of Figure 1 and is capable of associating with the handle of Figure 3 in any of its reversed positions.

Advantages

The present invention provides an assembly 60 comprising a latch mechanism unit and a handle unit for operating the same which can be applied to closure members such as refrigerator doors whether they are adapted to swing to the right or left or in any direction.

Furthermore, the same construction may be 65 used on lower as well as upper doors where it is desirable to use reversed handles.

The latch mechanism unit and the handle mechanism unit are entirely separate mechanically and either may be removed from the door for replacement or repair without removing the other.

Provision of the long curved cam lever on the handle mechanism enables only a slight move- 75

ment of the handle by an operator to be translated into an appreciable displacement of the latch mechanism levers so as to effect speedy and positive retraction of the latch bolt. This novel bolt actuation is applicable to any type of latch as well as the reversible latch illustrated in the drawings.

The reversible latch assembly of the present invention makes it unnecessary to manufacture or keep in stock different latch mechanism and handle units for different door arrangements and affords a decided economy over prior art arrangements as well as a simplification of manufacturing methods.

15 The invention may be embodied in other specific forms without departing from the spirit or essential characteristics thereof. The present embodiment is therefore to be considered in all respects as illustrative and not restrictive, the scope of the invention being indicated by the appended claims rather than by the foregoing description, and all changes which come within the meaning and range of equivalency of the claims are therefore intended to be embraced 25 therein.

What is claimed and desired to be secured by United States Letters Patent is:

20 1. A latch assembly for a closure member comprising a movable latch bolt, resilient means for urging said bolt in one direction, a pair of independently actuatable means each adapted to be operatively connected to said latch bolt, each of said independently actuatable means being operable to move said bolt against the action of said 25 resilient means, a reversible handle and a latch operating lever rigid with said handle operatively associated with only one of said last named means.

20 2. A latch assembly for a closure member comprising a movable latch bolt, resilient means for urging said bolt in one direction, a pair of movable arms extending in spaced relation each adapted to be operatively associated with said latch bolt, each of said arms being separately 15 actuatable to move said bolt against the action of said resilient means, a reversible handle and a latch operating lever rigid with said handle adapted to extend into the space between the arms and operatively engage only one of said 25 arms.

25 3. A latch assembly for use on closure members comprising a housing, a latch bolt slidably mounted in said housing and extending through an aperture in a wall of said housing, resilient means for urging said bolt in one direction toward said aperture and a pair of latch bolt operating arms arranged at opposite sides of said bolt each separately and operatively associated with said latch bolt in such a manner that actuation of either of said arms can move said latch bolt against the action of said resilient means.

20 4. A latch assembly comprising a housing, a latch bolt mounted for slidable movement within said housing and extending through an aperture in a wall of said housing, a projection on said latch bolt, an operating lever pivoted within said housing having one arm associated with said projection and another arm extending exteriorly of said housing and spring means for urging said bolt in one direction toward said aperture and said projection into contact with said one arm of said lever.

20 5. A latch assembly comprising a housing, a latch bolt mounted for slidable movement within said housing and extending through an aperture

in a wall of said housing, a pair of projections on said latch bolt, a pair of operating levers pivotally mounted within said housing each having one arm associated with a projection on said bolt and another arm projecting exteriorly of said housing and spring means for urging said bolt in one direction toward said aperture and said projections into contact with the respective first named arms of said levers.

6. In the latch assembly of claim 5, said projections being disposed on opposite sides of said bolt and said other arms of said levers extending generally parallel to the path of movement of said bolt.

7. In a latch assembly wherein the latch bolt operating mechanism is enclosed within a housing so as to be readily mountable and removable with respect to a closure or the like, a pair of individual operating members extending exteriorly of said housing, each of said members being operable to actuate said latch bolt operating mechanism.

8. In a latch assembly of the type wherein the latch bolt operating mechanism is enclosed in a housing which is seated in a recess in one edge wall of a closure member, a pair of latch bolt operating arms extending exteriorly of said housing and interiorly of said closure member, a handle assembly secured to the front wall of said closure member and a movable operating lever extending from said handle assembly into contact with one of said latch bolt operating arms.

9. A latch actuating mechanism for use on a closure member or the like comprising an escutcheon plate adapted to be secured to said closure member, a manually operable handle pivoted to said escutcheon plate and an elongated latch operating cam lever rigid with said handle and extending inwardly of said closure member, said latch operating lever being curved slightly in the plane of the path of its movement.

10. A latch mechanism comprising a slidable latch bolt and a housing enclosing mechanism for operating said bolt, a recess in said bolt and a spring seated in said recess, the other end of said spring abutting against a wall of said housing, and a pivoted operating arm adapted to be operatively connected to said bolt and extending exteriorly of said housing.

11. A latch assembly for use on closure members comprising a housing, a latch bolt slidably mounted in said housing and extending through an aperture in a wall of said housing, resilient means for urging said bolt in one direction toward said aperture, and a pair of latch bolt operating arms each separately and operatively associated with said latch bolt in such a manner that actuation of either of said arms can move said latch bolt against the action of said resilient means, each of said latch bolt operating arms being pivotally mounted upon said housing and extending exteriorly of said housing.

12. A latch assembly for use on closure members comprising a housing having a front wall and a side wall, a latch bolt slidably mounted in said housing and extending through an aperture in said front wall, resilient means for urging said bolt toward said aperture, a pair of pivot posts rigid with said side wall arranged at opposite sides of said slidable bolt and a pair of latch bolt operating arms mounted on said posts, each arm being separately and operatively associated with said latch bolt in such a manner that either of said arms can move said bolt against the action of said resilient means.

13. A latch assembly comprising a housing having a front wall, a reciprocable latch bolt within said housing and extending through an aperture in said wall, a projection on said bolt, 5
5 a latch operating lever pivotally mounted within said housing, an arm rigid with said lever interposed between said projection and said front wall and resilient means urging said bolt toward said aperture so that said projection is maintained 10
10 in contact with said arm and said arm serves as a stop for limiting movement of said bolt through said aperture.
14. A latch assembly comprising a reciprocable latch bolt, a pair of latch bolt operating levers 15
15 extending substantially parallel to the path of reciprocation of said bolt and to each other at opposite lateral sides of said bolt pivotally mounted for movement in planes generally parallel to the plane in which said bolt is reciprocable, rigid 20
20 projections extending from opposite lateral sides of said bolt, and arms rigid with said operating levers adapted to operatively engage said projections.
15. In a latch assembly for a closure member or the like, a reciprocable latch bolt, operating arms pivoted at opposite sides of said bolt for independent actuation of said bolt, said arms extending generally parallel to each other in 5
5 spaced relation, a reversible handle pivotally mounted upon said closure and an operating lever rigid with said handle extending into the space between said arms so as to operatively engage one of said arms when the handle is actuated. 10
16. In combination for use on a closure member, a reversible latch mechanism and a separate and distinct reversible handle mechanism, a cam lever in said handle mechanism extending into operative engagement with said latch mechanism 15
15 and of such design that each of said mechanisms is operatively associated with the other in all positions of either, and each of said mechanisms being readily removable from said closure member without at least partly removing the other. 20

THOMAS O. SCHRADER.
